(57) **CLAIM**

The ornamental design for an electrical junction box for a flow electroporation system, as shown and described.

DESCRIPTION

FIG. 1 is a perspective view of an electrical junction box for a flow electroporation system, showing my new design in an open configuration;

FIG. 2 is a perspective view thereof, illustrated in a closed configuration;

FIG. 3 is an exploded perspective view thereof;

FIG. 4 is a front elevational view of FIG. 2;

FIG. 5 is a rear elevational view of FIG. 2;

FIG. 6 is a left-side elevational view of FIG. 2;

FIG. 7 is a right-side elevational view of FIG. 2;

FIG. 8 is a top plan view of FIG. 2; and,

FIG. 9 is a bottom plan view of FIG. 2.
